LOUIS HUFFMAN, OF TORONTO, ONTARIO, CANADA.

WEB-CUTTING MECHANISM

Specification of Letters Patent. Patented May 18, 1915.

1,130,526.

Application filed June 30, 1911. Serial No. 286,140.

To all whom it may concern:

Be it known that I, Louis Huffman, of the city of Toronto, in the Province of Ontario, Canada, have invented certain new and useful Improvements in Web-Cutting Mechanism, of which the following is a specification.

The primary object of my invention is to devise rotary means for cutting a web of paper into sheets of predetermined length as the paper comes away from a printing press, but I have also in view a construction for that purpose which can be readily adapted to score, perforate, number or otherwise mark or impress a moving web of paper.

In describing my invention I will take as a concrete example mechanism arranged to completely sever the web of paper into sheets but it will be understood that, instead of cutters, perforators, scorers, numbering devices, or printing plates might be substituted.

The paper coming from a rotary printing press moves continuously and usually at a constant rate of speed hence great difficulty is experienced in cutting it evenly and in even lengths by means of stationary or ordinary rotary cutters. I overcome the difficulty by giving the cutting blades the following movements. One has a simple movement of rotation in a circular path about a fixed axis, the other has a rotary movement about an axis which is itself movable about a second axis. Thus both cutters may be caused to travel at the same rate of speed while in coöperative position and the last-mentioned cutter rotated on its axis to maintain it substantially normal to the path of the other cutter while they are in coöperative position.

Figure 1 is a longitudinal section of my apparatus. Fig. 2 is a plan view of the same. Fig. 3 is an end elevation of the same. Fig. 4 is an enlarged section illustrating the rotary die members in coöperation. Fig. 5 is a sectional detail illustrating the spring connection between one of the rotary die members and its driving gear. Fig. 6 is a cross-section on the line $a-a$ in Fig. 5. Fig. 7 is a cross-section on the line $b-b$ in Fig. 5.

In the drawings like figures of reference indicate corresponding parts in the different figures.

1 represents the frame of the machine suitably shaped to support the different parts. On this frame is suitably journaled

the shaft 2 to which is secured the drum 3 carrying at its periphery the die member 4 which in the construction illustrated is a shear blade. On this shaft is secured the gear wheel 5 meshing with the gear wheel 6 journaled on the frame 1 which in turn meshes with the gear wheel 7 which may be actuated in any suitable manner. The gear wheel 6 is preferably loose on the stud 8, 65 so that it may be slid longitudinally thereon to disengage it from the wheels 6 and 7. This enables me to rotate the drum 3 independent of its drive for adjustment and for other purposes. The coil spring 9 engages the gear wheel 6 and the head 10 on the stud and tends to maintain the gear wheel in position to engage the gears 5 and 7.

The die member 11 which coöperates with the die member 4 is carried and driven in the following manner: The shaft 12 is suitably journaled in the frame and is driven by the gear train 13 from the shaft 2, in the proportion of 2 to 1. On this shaft 12 the die member carriers 14 are supported being loose thereon. In these die member carriers the die member 11 is journaled by means of its trunnions 15. A driving connection is formed between one of the trunnions 15 and a pinion 16 in a manner which I will shortly describe. This pinion 16 meshes with the pinion 34 journaled on the adjacent die member support which meshes with the gear wheel 17 fast on the shaft 12. If the die member carriers 14 be held from rotation on the shaft 12 when the shaft is rotated the die member will be carried bodily around the axis of the shaft and at the same time by means of the gears 16, 17 and 34 will be rotated on its own axis. The gearing is so proportioned that the die member 11 rotates one and one half times on its own axis as it is carried once about the shaft 12. The result is that once in two revolutions of the shaft 12 the die members are brought into coöperative position, as shown in Fig. 4. This preferably occurs when the die member has an angular position of twenty-two and one-half degrees to the horizontal and the axis of the die member 11 is at an angle of forty-five degrees to the horizontal, though I do not, of course, confine myself to this exact relationship.

As the die member 11 is rotating on its own axis as it is carried around the shaft 12, 113 during the time the two die members are in coöperative relationship the angle of the die

member 12 to the horizontal is changed to correspond to the changes in the position of the die member 4, such change tending to maintain the die member substantially normal to the path of the edge of the die member 4. As, however, when the parts are proportioned as shown, the die member 4 is traveling around the shaft 12 on a circle of lesser radius than that of a circle drawn through its center from the center of the drum 3 I find that for similar arcs of travel the two die members do not move to and from the horizontal corresponding distances in equal periods of time. Hence means must be provided to vary the rate of travel of the die member 11 during such time as the two die members are in coöperative relationship. It is for this reason that the die member carriers 14 are loose on the shaft 12 as thus the die member carriers may be rocked independently of the shaft to give the desired variations in the rate of travel of the die member 11 to enable it to properly maintain its coöperative relationship with the die member 4.

A variety of mechanisms might be employed for the purpose of rocking the die member carriers 14. I illustrate, however, one which answers the purpose satisfactorily. Arms 18 are secured to the shaft 12 and in these arms is journaled a rock shaft 19. This rock shaft carries a segmental gear 20 meshing with a gear segment 21 formed on one of the die member carriers 14. Secured to the rock shaft 19 is a rock arm 22 which is provided with a projection 23 engaging in the cam groove 24 formed in the stationary cam disk 25. This cam will be so proportioned as to cause whatever variation may be necessary in the rate of travel of the die member 11 about the shaft 12 while the die members are in coöperative position.

The connection between the pinion 16 and the trunnion 15, hereinbefore referred to, is preferably arranged as follows: A pin 26 secured to the trunnion 15 fits within a recess 27 in the pinion thus allowing the latter a limited movement of rotation relative to the trunnion. A coil spring 28 has one end fitted into a hole in the pinion and its other end fitted in a hole in a disk 29 loose on the trunnion. A disk 30 is secured to the spindle and has a slot 31 formed therein through which passes the clamping screw 32 screwed into the disk 29. It is evident that by means of the clamping screw that the disk 29 may be adjusted relative to the disk 30 to regulate the tension of the coil spring 28. This coil spring tends to yieldingly press the die member 11 toward the die member 4 when they are in coöperative position to cause the cutting edges to hug one another sufficiently closely to produce a clean cut.

65 To insure the die members coöperating ac-

curately a finger 33 is provided on the die member 4 which engages over the die member 11, as shown particularly in Figs. 2 and 4.

What I claim as my invention is:—

1. The combination of a die-member rotatable on one axis; and movable in a closed path about a second axis; a rotary member fixed relative to its center of rotation and with which the die member is adapted to coöperate as it moves in said closed path; means for causing the die-member to rotate on its axis to maintain it substantially normal to the path of the coöperating member while the two members are in coöperative position; and means for causing the die member to move in its closed path at a speed greater than the speed of the coöperating member to compensate for the rotary movement of said die member on its axis. 70

2. The combination of a shaft; die-member carriers mounted thereon; a die-member journaled in said carriers; a rotary member fixed relative to its center of rotation and with which the die-member is adapted to coöperate as it is carried around said shaft; means for causing the die-member to rotate on its axis to maintain it substantially normal to the path of the coöperating member while the two members are in coöperative position; and means for causing the die member to move in its closed path at a speed greater than the speed of the coöperating member to compensate for the rotary movement of said die member on its axis. 80

3. The combination of a shaft; die-member carriers mounted thereon; a die-member journaled in said carriers; gearing whereby the die-member is carried about said shaft and simultaneously rotated on its axis thrice 90 as it is carried about said shaft twice; and a rotary member with which the die-member is adapted to coöperate. 100

4. The combination of a shaft; die-member carriers mounted thereon; a die-member journaled in said carriers; gearing whereby the die-member is carried about said shaft and simultaneously rotated on its axis thrice 110 as it is carried about said shaft twice; and a rotary member with which the die-member is adapted to coöperate, and means for varying the rate of travel of the die-member relative to the shaft to maintain the die-member substantially normal to the path of the coöperating member while the two 115 members are in coöperative position.

5. The combination of a shaft; die-member carriers mounted thereon; a die-member journaled in said carriers; gearing whereby said die-member is carried about said shaft 125 and simultaneously rotated on its axis thrice as it is carried about said shaft twice; and a rotary member geared to said shaft with which the die-member is adapted to coöperate. 130

6. The combination of a shaft; die-member carriers mounted loose thereon; a die-member journaled in said carriers; gearing connected with the shaft and die-member whereby the die-member rotates about said shaft and also rotates on its axis as it is carried about said shaft; a rotary member fixed relative to its center of rotation and with which the die-member is adapted to operate; means for rocking said die-member carriers on the shaft to maintain the die-member substantially normal to the path of the coöperating member while the two members are in coöperative position; and the gearing being arranged to cause the die member to move in its closed path at a speed greater than the speed of the coöperating member to compensate for the rotary movement of said die member on its axis.
7. The combination of a shaft; die-member carriers mounted thereon; a die-member journaled in said carriers eccentric to the shaft; gearing whereby the die-member is carried about said shaft and simultaneously rotated on its axis; a yielding driving connection between said die-member and its driving gear; and a rotary member with which the die-member is adapted to operate.

8. The combination of two die-members 30 adapted to coöperate rotatable about parallel axes and one also rotatable about a third axis whereby it may be maintained at a constant angle to the other member while they are in coöperative position; and means 35 whereby the second die member moves about its first axis at a greater speed than the first die member about its axis to compensate for the movement of the second die member about said third axis. 40

9. The combination of a rotary die-member; and a die-member movable at a greater rate of speed to coöperate therewith, and also movable to maintain a constant angle relative to the other member while they are 45 in coöperative position.

10. The combination of a die-member; and a die-member movable at a greater rate of speed to coöperate therewith, and also movable to maintain a constant angle relative to the other member while they are 50 in coöperative position.

Toronto, Ont. this 27th day of June 1911.
